E. H. HARPER

BOAT

Filed Sept. 10, 1925

UNITED STATES PATENT OFFICE.

ERNEST H. HARPER, OF OAKLAND, CALIFORNIA.

BOAT.

Application filed September 10, 1925. Serial No. 55,447.

This invention relates to "boats" and has especial reference to improvements in folding or collapsible boats in which the skin of the boat is made of a waterproof fabric.

One of the objects is to provide an improved rib and cooperating clip into which the rib is fastened to the gunwale thereof.

Another object is to provide an improved rib and cooperating clip into which the rib is fastened to the gunwale of a boat and thru which the rods of the gunwale pass.

Other objects, benefits and advantages will readily appear to persons skilled in the art from a consideration of the following description when taken into consideration with the drawing forming a part hereof, and wherein:

On the drawings:

Figure 1 is a perspective elevation of a canvas boat.

Figure 2 is an enlarged plan section.

Figure 3 is an enlarged section taken on line III—III of Figure 2.

Figure 4 is front elevation of the rib holding clip and a part of a rib secured therein.

Figure 5 is a section taken on line V—V of Figure 2, showing two longitudinal rods, forming reinforcements of the gunwale, threaded therethrough.

Figure 6 is a front elevation of the clip.

As shown on the drawings:

In all the views the same reference characters indicate similar parts. In the embodiment shown to illustrate my invention 10 is a boat, in this instance it is a boat having a canvas skin 11.

The boat has a plurality of spaced and properly bent transverse ribs 12. For the purpose of my invention the ends of the ribs are laterally displaced as shown at 13, for a purpose to be presently described.

The gunwale 14 is made of substantially horizontal rods 15 and 16 with the canvas turned over them as more clearly shown in Figures 3 and 5. The lower edge 17 may then be stitched, or otherwise fastened to the body part of the canvas between the metal clips 18 now to be described.

40 The clips 18 are intended to separately connect the gunwales to the ribs and each clip consists of a strip of metal bent centrally back upon itself with the side walls parallel and spaced apart. The side edges 19—19' and the end edges 20—20' are bent

toward each other with said edges substantially abutting, except at the upper part where openings 21 and 22 are left thru which to insert rods 15 and 16 respectively. The clip is riveted thru its lower end as 50 at 23 to the canvas of the boat. The upper part of the clip is held by the canvas fold 11'.

The wall 24 of the clip is perforated by an elongated opening 25.

When the ribs 12 are in their normal or natural positions, they are in a substantially vertical plane.

To insert the ribs in the holding clips 18 they are held at an angle to a vertical plane, 70 substantially as shown in broken lines in Figure 2, then the offset 13 of the rib ends are inserted in the respective oblong openings 25 of the clips. When the rib turns downwardly the least extent from this position, it 75 cannot be withdrawn from the clip, because it is locked therein by the offset end 13 passing behind the wall of the clip above the perforation.

In Figure 2 a plurality of inclined ribs 12 80 are shown by broken lines. These ribs are connected by a cord 26, also shown in broken lines. The ribs are initially entered in the clips when inclined to a greater extent than shown and then the cord 26 is pulled until 85 the ribs are moved into full line positions.

The clips 18 serve to lock the rib ends and also to secure the ribs to the salient edge or gunwale of the boat. The rod 15 over which the canvas is turned, as shown in Figure 3, 90 is divided into three sections; two end sections 15; only one of which is shown, and an intermediate section 16 with a gap 27 between.

The rods 15 and 15' are located in the 95 upper ends of the respective clips.

Rod 16 bridges the gap 27 and is located in the lower part of opening 21 as shown in Figures 3 and 5.

The gap 27 is left so that the boat may 100 be folded.

I am aware that many changes may be made, and numerous details of construction may be varied through a wide range without departing from the principles of this invention, I do not propose limiting the patent granted thereon otherwise than necessitated by the prior art or appended claims.

I claim as my invention:

1. In a boat, a pair of clips for attachment 110

- to the gunwale of the boat on opposite sides and having an opening to receive the respective ends of a rib, in combination with a removable rib having its ends insertable in 5 said openings when its mid portion is displaced laterally from its normal position and locked therein by its changed position when said portion is moved to its normal position.
19. 2. In a boat, a hollow clip for attachment to the gunwale of the boat and having a horizontally elongated opening thru its exposed wall in combination with a rib having an offset end insertable thru said opening 15 when the rib is substantially parallel with the longest axis of said opening and locked

in said opening when the rib is rotated to a position at an angle from said axis.

3. In a boat, a clip for attachment to the gunwale of the boat comprising a piece of 20 sheet metal bent back upon itself to provide two spaced walls, between which walls is inserted a rod comprising a part of the gunwale of the boat, and having an elongated opening in one wall thru which is inserted 25 the end of a rib, and a rib having an offset end insertable in said opening when the rib is in one plane and locked in said opening when the rib is rotated into another plane.

In testimony whereof I have hereunto 30 subscribed my name.

ERNEST H. HARPER.
